HIDE-STRETCHING CLAMP

Charles F. Fitzgerald, Beverly, Mass., assignor to
 United Shoe Machinery Corporation, Flemington, N. J., a corporation of New Jersey

Application October 27, 1942, Serial No. 463,511

14 Claims. (Cl. 24—84)

This invention relates to clips or other work clamping and holding devices and is illustrated as embodied in a clip for holding a hide or skin in stretched condition during drying thereof. While the invention is illustrated as embodied in a device for use in stretching hides and skins, it is to be understood that in various novel and useful aspects the invention is not limited to devices of the illustrated type.

As heretofore constructed, clips for holding hides and skins during drying thereof have commonly included, as an important element thereof, a lever member to engage and clamp the edge of the work piece in such manner as to adjust the clip to variations in the thickness of the portion being clamped. In those cases where the clamped portion of the work piece is unusually thin there may be failure to engage the work piece with sufficient pressure to hold the latter while, on the other hand, thick pieces may require such an effort in closing the clamping lever as to slow up the operator and in time result in damage to the clip through unusual wear and bending or other distortion of the parts. Where attempt is made to overcome these objections by providing a yielding element or elements to engage one surface of the work piece, it is possible in such prior constructions to secure only fair results while the parts are new and then only through the provision of a relatively complicated structure, costly to make and maintain in good condition.

It is an object of this invention to provide a clip of the kind described having relatively few parts, and one which will operate with a minimum of wear, and provide a highly effective device for the purpose intended.

To these ends and in accordance with an important feature of the invention, means, including a wedge, is provided to effect closure of the jaws of the clip on a work piece in a manner most effectively to accommodate the clip to variations in the thickness dimensions of the work pieces undergoing treatment. Conveniently, the wedge member may be operated by a spring and/or by a finger piece to initiate the clamping operation and to give the preliminary stretching to the hide or skin, the effect of the wedge being such that the firmer the skin is stretched the greater the clamping action, whereby the hide or skin is securely held in place on the stretching frame. It is a further important feature of the invention that the work piece is gripped more firmly during shrinkage due to drying thereof, the wedge operating under these

conditions to press the jaws of the clip more firmly toward each other.

These and other important features of the invention and novel combinations of parts will now be described in detail in the specification and then pointed out more particularly in the appended claims.

In the drawing,

Fig. 1 is a view, partly in side elevation and partly in section, of the novel clip of the present invention, showing the clip ready for use;

Fig. 2 is a view similar to Fig. 1 showing the clip engaged with a marginal portion of a hide or skin;

Fig. 3 is a sectional view along the line III—III of Fig. 1 but on a substantially larger scale;

Fig. 4 is an end view of the bolt 32 of Fig. 3; and

Fig. 5 illustrates a species which is simpler in construction, since it omits the self-adjusting feature of the clip shown in Figs. 1 to 3, inclusive.

Upon reference to Figs. 1 to 3, inclusive, it will be seen that the clip, which is specially designed to engage and hold a hide or skin portion during drying of the latter, comprises a main frame or body part 6 having rigidly secured thereto an upper stationary jaw 8 carried between side walls 10 of the body part. There is also a bottom wall or floor 12 for slidably supporting a wedge member 14 utilized in lifting and lowering a movable jaw 16 toward and from the upper jaw 8 to grip a portion of a work piece, such as that indicated at 18 (Fig. 2), and to release the same. The gripping and holding effect of the two jaws is increased by the provision of serrations 19 on the work engaging surface of the lower jaw 16.

To facilitate operation of the wedge 14, a finger loop 20 is provided which is either fixedly secured to the wedge member 14 or made integral therewith as in the construction shown. Obviously a pull upon the finger loop 20 toward the left in Figs. 1 and 2 will result in lifting the lower jaw 16 to effect gripping of the work piece 18. As indicated, the jaw 16 is limited to vertical movement by pins 19a secured to the rear part of the jaw 16 and slidable in vertical slots 21 in the side walls 10.

To hold the combined wedge member 14 and loop 20 in assembled relation with respect to the body part 6 of the clip there is provided, in the construction illustrated in Figs. 1 and 2, a latch 22 having an upturned end portion 23, the body part 6 being slotted at 24 to receive the upturned end portion 23. Conveniently the latch 22 is se-

cured to a forwardly extending portion 25 of the loop 20 by means of a spring member 26, the latch 22 having a finger piece 28 extending rearwardly therefrom so that the latch may be readily released from the body portion 6 simply by upward pressure on the finger piece 28 accompanied by a corresponding downward pressure on the adjacent portion 25 of the loop 20. Upon thus releasing the latch 22 from the body portion 6, the loop 20 and wedge 14 may be moved to the left relatively to the body portion to actuate the lower jaw member 16.

Preferably, and as shown, means is provided to move the finger loop 20 and wedge 14 toward the left in Figs. 1 and 2 upon releasing the latch 22 from the body part 6 of the clip, said means being conveniently in the form of a relatively strong spring 30 of the clock type, said spring having one end secured to a cylindrical bolt 32 upon which the spring is wound and its other end secured to the combined finger loop 20 and wedge member 14. Hence, as soon as the latch 22 is released, the spring 30 retracts the wedge 14 and thus operates the lower jaw 16 with its serrations 19 into work gripping relation with respect to the upper jaw 8. It will be readily understood that, upon shoving the wedge member 14 to the right in Figs. 1 and 2 by pressure upon the finger loop 20, the work piece is released and the spring 30 is rewound. Incidentally, this makes it necessary to shove the finger loop 20 and the wedge 14 far enough to the right in said Figs. 1 and 2 to reengage the latch 22 with the body part 6 at the slot 24. The last-described movement of the loop 20 and wedge 14 normally takes place to release the work piece at the end of a drying operation upon the hide or skin, it being understood in this connection that many clips are used to engage different portions of the hide or skin and stretch these portions in various directions, the purpose being to secure the hide or skin in stretched condition upon a foraminous stretcher frame where the hide or skin is left to dry.

In order to hold the clip in its adjusted relation to the stretcher frame, the body part 6 of the clip is provided with a hook member 36 which may be readily engaged in one of the openings or slots of the foraminous frames provided for stretching hides and skins.

To facilitate assembling of the spring 30 with the body part of the clip and also the initial tensioning of the spring, the cylindrical bolt 32 is provided with a square-shouldered end 42 (Figs. 3 and 4) receivable in a correspondingly shaped opening in one of the side walls 10. The other end of the bolt 32 has a reduced screw threaded portion 44 rotatably receivable in an opening in the other side wall 10 and projecting beyond the same so that a nut 46 may be applied to retract the bolt 32 toward the left in Fig. 3 and hold it in properly assembled relation to the side walls of the body part 6. Upon loosening the nut 46, the bolt 32 may be moved to the right in Fig. 3 until the shouldered portion 42 is displaced completely out of its socket or slot so that it may be rotated by application of the proper tool to tension the spring 30, the bolt being held by the tool at the end of the tensioning operation in a position such that the shouldered portion 42 may reenter its socket upon tightening the nut 46.

While, in the preferred species of the invention, spring means is provided to give the initial setting or clamping action of the clip with re-

spect to the work piece, it is obvious that the spring may be omitted, as shown in Fig. 5, in which case the operator must manipulate the combined loop 20 and wedge member 14 to cause engagement of the work piece through upward movement of the lower jaw 16. To facilitate this manipulation of the loop and wedge member by the operator, there is conveniently provided a thumb rest 50 extending upwardly from the upper wall of the body part 6 of the clip. This enables the operator to effect preliminary engagement of the clip with respect to the work piece utilizing only one hand for the purpose. For holding the finger piece 28 and wedge 14 in adjusted relation with respect to the body part 6 of the clip, the finger loop 20 has its forwardly projecting end 51 provided with a rounded tooth element 52 to engage slidably and adjustably and in a selective manner with any one of the corrugations 54 on the lower face of the upper wall of the body part 6.

In stretching a hide or skin with the aid of clips of the construction shown in Figs. 1, 2 and 3 of the drawing, the operator positions the clip with the upper jaw 8 thereof engaging the upper or grain surface of the hide or skins at a marginal portion thereof and then presses the finger piece 28 and the adjacent portion 25 of the loop member 20 toward each other, thereby effecting release of the latch 22 from its slot 24. Such release of the latch 22 permits the spring 30 to operate the wedge 14 and thus effect upward movement of the jaw 16 into clamping relation with respect to the margin of the work piece and the upper jaw 8, it being understood that the other hand of the operator holds the body part 6 of the clip in selected relation to the margin of the work piece. Having thus effected preliminary engagement of the clip with respect to the work piece, the operator pulls on the finger loop 20 to stretch the work piece, such pulling on the loop member 20 having the effect also of further tightening the grip of the jaws on the work piece through the action of the wedge 14, so that by the time the work piece is properly stretched in its engaged portion the margin thereof is gripped with a progressively increasing firmness having the effect of embedding the serrations 19 in the flesh surface of the hide or skin, so as to insure against slipping of the clip with respect to such work piece. At the end of the stretching by each clip, the latter is located with respect to the stretcher frame by engaging the hook member 36 in one of the openings or slots therein. During drying of the work piece such as a hide or skin, the latter shrinks in area and to some extent in thickness. However, the clip does not lose its hold since, during any shrinkage in thickness, the wedge 14 maintains the grip of the lower jaw through further pull of the spring 30. When it is desired to release the work piece, the operator shoves to the right on the finger loop 20 thereby moving the wedge to the right and permitting the lower jaw 16 to drop away from the work piece and to release it, this movement of the finger loop 20 and of the wedge 14 taking place while the body part 6 of the clip is held stationary because of the engagement of the hook member 36 with the stretcher frame.

The operation of the clip shown in Fig. 5 is very similar to that just described, the only difference being that the operator must give the preliminary movement of the wedge relative to the body part 6 of the clip, by proper manipula-

tion of the finger loop 20 in relation to the thumb rest 50 on the body part of the clip.

Having described my invention, what I claim as new and desire to secure by Letters Patent of the United States is:

1. In a clamping device, the combination with a pair of gripper jaws, one of said jaws being loosely mounted on said device, of a finger piece for positioning said device in operative relation to a work piece, said finger piece being releasable at will for movement relatively to said gripper jaws and having a portion formed as a wedge to operate said gripper jaws to grip or release the work piece in response to such movement of the finger piece, said wedge being arranged to increase the pressure of said gripper jaws on the work in response to a pull of said device on the work.

2. In a clamping device, a body member, an upper jaw on said body member, a lower loosely mounted jaw, and a wedge member in contact with the body member and beneath said lower jaw, said wedge member being operative to cause relative approaching movement of the jaws with respect to each other, upon relative sliding movement of the jaws and said wedge member, whereby a portion of a work piece is gripped and an increase of the clamping pressure of the jaws on the work is effected by the action of said wedge member in response to the pull of said device on the work.

3. In a clamping device, a main body member, an upper jaw on said body member, a lower jaw, a movable wedge member slideable on said body member and operative to control relative approaching and separating movements of the jaws with respect to each other, and a finger loop piece to operate the movable wedge, the arrangement being such that a pull on the finger loop piece away from a work piece placed between the jaws operates the wedge member to cause firm clamping action of the jaws against a portion of such work piece.

4. In a clamping device for gripping a work piece, an upper jaw, a lower jaw, a movable wedge member to control relative approaching and separating movements of the jaws with respect to each other, a finger piece to operate the movable wedge member, and a latching device to hold the wedge member in its initial position in which the jaws are spaced substantially from each other, said latching device being readily operable to release the wedge member so that the latter may be operated to cause clamping pressure of the jaws on the work piece.

5. In a clamping device for gripping a work piece, an upper jaw, a lower jaw, a movable wedge member to control relative approaching and separating movements of the jaws with respect to each other, a finger piece for moving the wedge member, a latching device associated with the finger piece for holding the wedge member against movement out of initial position in which the lower jaw is spaced substantially from the upper jaw, said latching device being readily operable to release the wedge member so that the latter may be operated to cause clamping pressure of the jaws on the work piece, and a spring means for thus operating the movable wedge member upon release of the finger piece by said latch device.

6. In a clamping device for gripping a work piece, an upper jaw, a lower jaw, a movable wedge member to control relative approaching and separating movements of the jaws with respect to each other, and a finger piece to operate the mov-

able wedge member, the arrangement being such that a pull on the finger piece away from a work piece placed between the jaws operates the wedge member to cause clamping pressure of the jaws upon a portion of such work piece, said clamping device having a hooked portion to engage a work piece stretching frame and to retain the clamping device on said frame against the pull of the tensioned work piece, said finger piece and wedge member

10 member being movable by a push on the finger piece against the resistance of the frame to release the clamping pressure.

7. In a clamping device for gripping a work piece, a main frame, an upper jaw on said main frame, a lower movable jaw having a serrated work engaging surface, and a movable wedge member between a portion of the main frame and the lower jaw for moving the lower jaw toward the upper jaw whereby a portion of a work piece may be gripped.

15 8. In a clamping device for gripping a work piece, a main frame, an upper jaw on said main frame, a lower movable jaw, a movable wedge member to lift the lower jaw toward the upper jaw and away from a portion of the main frame, and a finger piece secured to the movable wedge member, the arrangement being such that a pull on the finger piece away from the jaws operates the wedge member to press the lower jaw firmly against a portion of such work piece interposed

20 between the jaws.

9. In a clamping device for gripping a work piece, a main frame having a fixed upper jaw, a lower jaw movable toward and from the upper jaw, a movable wedge member to lift the lower jaw toward the upper jaw, a finger piece secured to the movable wedge member, and a latching device associated with the finger piece to hold the wedge member in its initial position in which the lower jaw is spaced substantially from the upper jaw, said latching device being readily operable to release the finger piece so that the wedge member may be operated to press the lower jaw toward the upper jaw.

45 10. In a clamping device for gripping a work piece, a main frame having a fixed upper jaw, a lower jaw movable toward and from the upper jaw, a movable wedge member to lift the lower jaw toward the upper jaw, a finger piece secured to the movable wedge member, a latching device associated with the finger piece to hold the wedge member in its initial position in which the lower jaw is spaced substantially from the upper jaw, said latching device being readily operable to re-

50 lease the finger piece so that the wedge member may be operated to press the lower jaw toward the upper jaw, and spring means for thus operating the movable wedge member upon release of the finger piece by said latch device.

60 11. In a clamping device, a main frame, an upper jaw fixed to said main frame, a lower movable jaw, a movable wedge member to lift the lower jaw toward the upper jaw, and a finger piece arranged to operate the movable wedge member, the arrangement being such that a pull on the finger piece away from the jaws operates the wedge member to close the jaws upon a work piece interposed between the jaws, said main frame having a hooked portion to retain the

65 70 clamping device upon a work piece stretching frame against the tension of such work piece, and said finger piece and wedge member being movable relatively to said jaws by a push on said finger piece against the resistance of the stretching frame to open the said jaws.

12. In a clamping device, a main frame having a fixed jaw, a loosely mounted jaw having serrations on its work engaging face, said loosely mounted jaw being arranged parallel to the fixed jaw and being mounted for free normal movement toward said fixed jaw, a wedge member between the loosely mounted jaw and a portion of the main frame for moving said movable jaw to close the jaws on a work piece, and a finger piece for thus operating said wedge member by a pull in a direction away from said work piece.

13. In a clamping device, a main frame having a passage therethrough, one end of said passage having a wall to constitute a fixed jaw, a loosely mounted jaw arranged to face said fixed jaw, a wedge member between another wall of said one end of said passage and the loosely mounted jaw,

and a finger piece inserted within the other end of the said passage and attached to the wedge member, said finger piece being adapted to open or close the jaws by means of the wedge member.

14. In a clamping device, a main frame having a fixed jaw and a portion parallel to said fixed jaw, a finger loop piece slidably engaging the main frame, a wedge member also slideable on the main frame and under the control of said finger loop piece, and a second jaw movable relative to the first jaw, said wedge member being interposed between said second jaw and said portion of the main frame, the arrangement being such that a push on the finger loop piece toward the jaws will serve to open the jaws.

CHARLES F. FITZGERALD.
